(57) **CLAIM**

The ornamental design for a RDC adapter key, as shown and described.

DESCRIPTION

FIG. 1 is a front perspective view of a RDC adapter key showing my new design;

FIG. 2 is a rear perspective view of FIG. 1;

FIG. 3 is a top view of FIG. 1;

FIG. 4 is a front view of FIG. 1;

FIG. 5 is a side view of FIG. 1;

FIG. 6 is a rear view of FIG. 1.;

FIG. 7 is a cross sectional view along line 7—7 of FIG. 5;

FIG. 8 is a cross sectional view along line 8—8 of FIG. 6;

FIG. 9 is front perspective view of a RDC adapter key showing in its environmental use;

FIG. 10 is a rear perspective view of FIG. 9;

FIG. 11 is a top view of FIG. 9;

FIG. 12 is a front view of FIG. 9;

FIG. 13 is a side view of FIG. 9; and,

FIG. 14 is a rear side view of FIG. 9.

The broken lines environment in FIGS. 9—14 is for illustrative purpose only and forms no part of the claimed design.
